(57) **CLAIM**

The ornamental design for a folding table, as shown and described.

DESCRIPTION

FIG. 1 is a front view of a folding table showing my new design in a fully open position of use;

FIG. 2 is a rear view in a fully open position thereof;

FIG. 3 is a left view in a fully open position thereof;

FIG. 4 is a right view in a fully open position thereof;

FIG. 5 is a top view in a fully open position thereof;

FIG. 6 is a bottom view in a fully open position thereof;

FIG. 7 is a perspective view in a fully open position thereof;

FIG. 8 is a left view in a half open position thereof; and,

FIG. 9 is a perspective view in a half open position thereof.

In the drawings, the broken lines represent portions of the folding table that form no part of the claimed design.

1 Claim, 9 Drawing Sheets
